DESIGN FOR A WATCH CRYSTAL INSERTING MACHINE

Julius Simon, Rochester, N. Y., assignor to
Germanow-Simon Machine Co., Rochester,
N. Y., a co-partnership of New York

Application July 4, 1945, Serial No. 120,522

Term of patent 14 years

(Cl. D42—1)

To all whom it may concern:

Be it known that I, Julius Simon, a citizen of the United States of America, residing at Rochester, in the county of Monroe and State of New York, have invented a new, original, and ornamental Design for a Watch Crystal Inserting Machine, of which the following is a specification, reference being had to the accompanying drawing, forming part thereof.

Fig. 1 is a side elevational view of a watch crystal inserting machine, showing my new design; and

Fig. 2 is a front elevational view thereof.

I claim:

The ornamental design for a watch crystal inserting machine, substantially as shown.

JULIUS SIMON.
